(57) **CLAIM**

The ornamental design for a packaging carton as shown and described.

DESCRIPTION

The file of this patent contains at least one drawing executed in color. Copies of this patent with color drawing(s)/photograph(s) will be provided by the Office upon request and payment of the necessary fee.

FIG. 1 is a top, front, right perspective view of a first embodiment of a packaging carton showing our new design;

FIG. 2 is a top plan thereof;

FIG. 3 is a bottom plan thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a bottom, left, rear perspective view thereof;

FIG. 9 is a top, front, right perspective view of a second embodiment of a packaging carton showing our new design;

FIG. 10 is a top plan thereof;

FIG. 11 is a bottom plan thereof;

FIG. 12 is a front elevational view thereof;

FIG. 13 is a rear elevational view thereof;

FIG. 14 is a right side elevational view thereof;

FIG. 15 is a left side elevational view thereof;

FIG. 16 is a bottom, left, rear perspective view thereof;

FIG. 17 is a top, front, right perspective view of a third embodiment of a packaging carton showing our new design;

FIG. 18 is a top plan thereof;

FIG. 19 is a bottom plan thereof;

FIG. 20 is a front elevational view thereof;

FIG. 21 is a rear elevational view thereof;

FIG. 22 is a right side elevational view thereof;

FIG. 23 is a left side elevational view thereof;

(Continued)

FIG. 24 is a bottom, left, rear perspective view thereof; FIG. 25 is a top, front, right perspective view of a fourth embodiment of a packaging carton showing our new design; FIG. 26 is a top plan thereof; FIG. 27 is a bottom plan thereof; FIG. 28 is a front elevational view thereof; FIG. 29 is a rear elevational view thereof; FIG. 30 with the following paragraphs: FIG. 31 is a left side elevational view thereof; and, FIG. 32 is a bottom, left, rear perspective view thereof. In the drawings, the broken lines are shown for the purpose of illustrating parts of the packaging carton that form no part of the claimed design.
